UNITED STATES PATENT OFFICE.

HERMON E. CUNNINGHAM, OF PHILADELPHIA, PENNSYLVANIA.

CARD-FORMING MACHINERY.

SPECIFICATION forming part of Letters Patent No. 437,021, dated September 23, 1890.

Application filed August 24, 1889, Serial No. 321,858. (No model.)

To all whom it may concern:

Be it known that I, HERMON E. CUNNINGHAM, a citizen of the United States, residing in the city and county of Philadelphia, State 5 of Pennsylvania, have invented a new and useful Improvement in Card Setting or Forming Machinery, which improvement is fully set forth in the following specification and accompanying drawings.

10 My invention consists of improvements in the feeding and guiding device of a woolen, cotton, or other card setting or forming machine, the object of the invention being to so feed and guide the band or backing that the 15 wires or teeth enter the same in such manner that when the backing is wound or wrapped around a drum or mandrel the wires are parallel with the axis of said drum or mandrel and both points of each wire simultaneously 20 enter the stock to be carded.

Figure 1 represents a front view of the portion of a card-forming machine embodying my invention. Fig. 2 represents a similar view, the parts being in different position. Fig. 3 25 represents a side elevation thereof. Fig. 4 represents a vertical section on line x x , Fig. 1, showing a part of the bearings of the rollers and their pivotal support. Fig. 5 represents a piece of the work produced.

30 Similar letters of reference indicate corresponding parts in the several figures.

Referring to the drawings, A designates a portion of the frame of a card-forming machine.

35 B designates a saddle, on which are mounted the rollers C, for feeding and guiding the band or backing in which card-teeth are inserted, said saddle being connected with an upright of the frame A by means of a pivoted bolt D, 40 whereby it may be turned on the same as an axis, and thus be placed in oblique position, as shown in Fig. 1, or in horizontal position, as shown in Fig. 2.

One of the journals of the upper roller C is 45 extended outside of its bearings on the saddle B, and has secured to its end a ratchet F, and carries a loose arm G, the latter having a spring-pressed pawl H mounted upon it, the same being adapted to engage with the teeth 50 of the ratchet F.

J designates a carriage, which is supported

upon the frame A and receives motion in a line parallel with the rollers C.

Secured to or formed with the carriage J is a wedge-shaped block K, which engages with 55 a wedge-shaped block L, the latter depending from and secured to an elbow M, the upper limb N whereof engages with or bears against the under side of the arm G near the outer end thereof.

60 The journals of the lower roller C rest on boxes P, against which bear the springs Q, the tension of which latter is regulated by screws R, it being evident that the sides of the saddle B are properly recessed to receive said journals, the boxes, springs, and screws, and by the operation or rotation of said screws the 65 tension of the springs may be varied and the lower roller C adjusted near to or farther from the upper roller C.

70 In the saddle B is a segmental slot S, which receives a bolt T, which is connected with the adjacent portion of the frame A, so that by means of a nut U on said bolt the saddle may be retained in either of its adjusted positions, 75 whether horizontal or oblique. It will be seen that the strip of material forming a band or

80 backing may be fed through and guided by the roller C in a direction at a right angle to said rollers, whereby the card-teeth may be subsequently inserted in said backing at right angles to the sides thereof. When, however, it is desired to insert card-teeth in the 85 backing where the latter will be subsequently wrapped or wound spirally around the drum or mandrel, it is essential to feed and guide said band to the card-forming machine in an oblique direction, as shown in Fig. 1. For this purpose the saddle B is placed in the oblique position shown in Fig. 1, the nut U having 90 been properly previously loosened and afterward tightened, when the adjustment of the saddle is completed. The backing will now be presented to the card-forming machine in such manner that the teeth are inserted in 95 an oblique direction, as will be seen dotted in Fig. 1. When the backing is wrapped or wound around the drum or mandrel, the card-teeth will assume a position parallel with the axis of said drum or mandrel, as illustrated 100 by the dotted diagram, Fig. 5.

The ratchet F receives intermitting motion

- by the action of the pawl H, arm G, blocks L K, and carriage J, it being noticed that as the carriage is advanced in one direction the inclined side of the block K presses against the 5 inclined side of the block L, thus raising said block L, and consequently elevating the elbow or lifting piece M. This raises the arm G and causes the pawl H to move the ratchet F a distance equal to the throw of said arm G.
- 10 The carriage J now returns, whereby the block L, and consequently the elbow M, are permitted to drop, thus releasing the arm G and permitting it and the pawl H to lower, so that said pawl may take hold of another tooth preparatory to its next operation, it being evident that the motion of the ratchet is imparted to the upper roller C, between which and the lower roller C the backing is passed to the card-forming machine. When the saddle is 15 placed in oblique position, as in Fig. 1, the connected parts thereof assume a similar position. This, however, does not affect the action of the elbow M upon the arm G, as said elbow has a free connection with said arm.
- 20 25 The elbow M, which carries the block L, has a depending stem V, which passes freely through a slot W in the carriage J and a recess X in the base of the frame, said slot W permitting the carriage to pass said stem V.
- 30 Having thus described my invention, what I claim as new, and desire to secure by Letters Patent, is—

1. In a feeding and guiding device for a

card setting or forming machine, a saddle with parallel rollers in connection therewith, said saddle having an extended end pivotally attached to the frame and through which the extended journal of one of said rollers projects to receive operating mechanism therefor, substantially as described.

2. Feeding and guiding rollers and a support therefor, in combination with a ratchet mounted on the journal of one of said rollers, a pawl engaging with said ratchet, a swinging arm carrying said pawl, a lifting-piece engaging said arm, an inclined block secured to said lifting-piece, and a carriage which is provided with an inclined block adapted to engage the inclined block on the lifting-piece, the latter being sustained on the frame, substantially as described.

3. In a card-forming machine, the feeding and guiding rollers, combined with a pawl and ratchet for operating the guiding and feeding rollers of a card setting or forming machine and a rising and falling piece which engages with the pawl-carrying arm, said piece being guided in the frame and provided with an inclined block which is connected to a carriage, the parts named being combined substantially as described.

HIERMON E. CUNNINGHAM.
